YARN CARRIER OF KNITTING MACHINES

Charles G. Newton, Hamilton, Ontario,
CanadaApplication December 16, 1936, Serial No. 116,062
In Canada October 18, 1936

11 Claims. (Cl. 66—126)

This invention relates to improvements in yarn carriers of knitting machines. A yarn carrier comprises a flat tapering shank and a head by means of which it is secured to the knitting machine in a bank or banks with other carriers, and its function is to guide the yarn on the final part of the course from a yarn package or cone to the loop forming elements of the machine. These guide means include a longitudinal groove in one face of the shank and which flaringly terminates in an opening or eye near the tip, and a tube leading from the opening, through the tip and to a point beyond the tip. In the conventional carrier, this tube is passed through a substantially conforming eyelet opening into the aforesaid eye and is soldered or otherwise fixed in position.

Yarns are fed through these tubes, and although formed of hardened steel the tubes nevertheless wear, not only internally but in time to have cross grooves at the tube mouths from which the yarn emerges and alternates in the direction of its delivery resulting from the reciprocation of the carriers in the machine. Consequently, the tubes must be discarded from time to time and replaced, and such an operation not only necessitates the removal of the carriers from the machine but the solder must also be fused in order to first release the worn tubes that new ones may be inserted and soldered in place. Another objection to the conventional carrier is that, unless great care is exercised in the replacement operation, the heat applied in soldering will soften the hardened tubes.

One important object of the invention is to provide means for readily replacing the carrier tubes and in that operation to obviate the necessity of removing the carriers from the machine.

Another important object is to provide a carrier in which wear of the mouth of the tube is reduced.

A further important object is to provide a carrier that is simple, durable, efficient, and inexpensive to produce.

With the above and other objects in view as will be hereinafter apparent, the invention comprises in general certain novel elements of construction and combination of parts hereinafter fully described, illustrated in the accompanying drawing and specifically claimed.

Figure 1 is a view in front elevation of a yarn carrier constructed in accordance with the invention;

Fig. 2 is an enlarged view of a lower portion of the carrier as shown in Fig. 1;

Fig. 3 is a median section taken on the line 3—3 of Fig. 2;

Fig. 4 is a cross-section on the line 4—4 of Fig. 2;

Fig. 5 is a cross-section on the line 5—5 of Fig. 2;

Fig. 6 is a cross-section on the line 6—6 of Fig. 2; and

Fig. 7 is an elevational view of the tube.

In its present embodiment, the improved carrier comprises a conventionally proportioned flat tapered shank 10 formed with a head 11 by which it is secured to the knitting machine. These carriers are arranged in banks and are usually each bent downwardly at a point where a yarn 15 guide groove 12 widens or flares, but as the angles vary widely at which certain shanks are so bent and other shanks are sometimes substantially straight, the carrier is here illustrated as straight. The carriers are usually produced in unbent form.

Near its lower end, the groove 12 deepens or flares toward an eye 13 formed in the shank close to its tip and extending through from one flat side to the other. A yarn carrier tube 15 is disposed in a tip 14 or that part of the shank between the eye 13 and its lower end. This tube is revolvable about its longitudinal axis in a core 16 and slideable along said axis in and out of the core. When in position, the tube protrudes both into the eye 13 and beyond the lower end of the tip 14.

A collar 17 on the tube 15 has a lower shoulder which, when the tube is in proper position, abuts a flat face 18 of the eye 13. The face 18 provides a seat for the shoulder and constitutes a limiting stop for the tube.

On the face of the shank opposite to the face having the groove 12, is a snap spring 19 which extends nearly across the eye 13 but terminates short of the face 18 at a distance therefrom substantially equaling the length of the collar 17. This spring is curved into the eye toward which it is biased so that the lower end of the spring is disposed opposite the upper or spring-detent shoulder of the collar.

By merely flexing back the spring, the tube is free to be withdrawn from the core 16. This operation may be effected by the introduction of any suitably pointed instrument of a character enabling it to be introduced into the eye. Similarly, but without the assistance of an instrument, the extracted tube may be quickly replaced by another tube, during which operation the tip of the spring merely slides over the collar until the tube reaches operative position, when the

spring tip snaps into the normal position previously set forth.

It is preferable to set the spring 19 so that no tension or pressure is maintained against the tube or its collar while the tube is in operative position. This leaves the tube free to rotate, whereby the motion of the machine combined with the running yarn 20 causes the tube to more or less irregularly but also substantially constantly alter its position about its axis, a movement which obviates the tendency of the mouth of the tube to become cross-grooved and thus prolongs its life.

Of course, the improvements specifically shown and described by which I obtain the above results, can be changed and modified in various ways without departing from the invention herein disclosed and hereinafter claimed.

I claim:

1. In a yarn carrier, a tube readily removably disposed in the carrier tip, means on the tube cooperating with the tip for limiting movement of the tube in one direction relative to the tip, and means including a spring on the tip for snap locking action relative to a portion of the tube for limiting movement of the tube in the opposite direction and operative to provide for movement of the tube in said opposite direction for removal of the tube from the tip.

2. A yarn carrier guide comprising a finger having a portion constituting substantially a journal for a finger tip tube, a finger tip tube journaled by said portion for movement of the tube about its longitudinal axis relative to the finger in response to yarn guiding movement of the guide and an effect of the yarn on the tube during said movement, and means providing cooperating shoulders transversely of the guide on the finger and the tube, respectively, for positively locking the tube longitudinally relative to the finger within definitely limited distances in both directions and providing for the ready separation of the tube from the finger, the said locking shoulder on the guide being carried by a spring and held by the spring to be freely spaced from the cooperating lock shoulder on the tube in the operative locking positions of the shoulders.

3. The combination in a yarn guide for knitting machines of a guide member having an eye and an aperture extending from said eye to the lower end of the member, a tube in said aperture, said eye, tube and member arranged for insertion and removal of the tube into and from the aperture through said eye, and a latch for holding said tube in said aperture lying normally in the path taken by said tube during withdrawal from said aperture but readily removable from said path.

4. The combination in a yarn guide for knitting machines of a guide member having an eye and an aperture extending therefrom to the end of the member, a tube in said aperture, and a flat spring fastened to said guide member and extending to a point adjacent a transverse surface of said tube for holding the tube in and readily releasing it from said aperture.

5. The combination in a yarn guide for knitting machines of a guide member having an eye and an aperture extending therefrom to the end

of the member, a tube in said aperture, and a flat spring fastened to one face of said member and curving into said eye to a point adjacent a transverse surface of said tube for holding the tube in and readily releasing it from said aperture.

6. The combination in a yarn guide for knitting machines of a guide member having an eye and an aperture extending from said eye to the lower end of the member, a tube revoluble in said aperture under the action of yarn in use, said eye and member arranged for insertion and removal of the tube into and from the aperture through the eye, and a latch for holding said tube in said aperture lying normally in the path taken by said tube during withdrawal from said aperture but readily removable from said path.

7. The combination in a yarn guide for knitting machines of a guide member having an eye and an aperture extending therefrom to the end of the member, a tube revoluble in said aperture under the action of yarn in use, and a flat spring fastened on one face of the guide member and curving into said eye to a point adjacent a transverse surface of said tube member for holding the tube member in and readily releasing it from said aperture.

8. The combination as set forth in claim 7 and in which the tube member and guide member have abutting transverse surfaces for revolvably supporting the tube member in the bore.

9. In combination, a yarn guide for knitting machines having a non-bifurcated tip at the end from which the yarn is fed to the knitting needles, an eye removed from said tip, an aperture running from said eye through said tip, a yarn feeding tube in said aperture capable of being inserted into and removed therefrom but only through said eye and having a shouldered portion adapted to limit the travel of the tube in the aperture in the direction in which it moves when being inserted into the aperture, and a spring member positioned relatively to said guide to adapt it to engage the shouldered portion of said tube on the opposite side from the side adapted to abut the guide to prevent the tube from moving materially, during use, in the direction in which it moves in being removed from said aperture.

10. The combination in a yarn guide for knitting machines of a guide member having an opening in its tip in which a yarn tube is removably mounted, and a spring member attached to said guide and mounted to move transversely of the normal plane of motion of said guide into contact with a shoulder on said thread tube to hold the tube against motion upward in the guide.

11. The combination in a yarn guide for knitting machines of a guide member having an opening for receiving a yarn tube and extending from the free tip of the guide longitudinally thereof, a yarn tube in said aperture having a shoulder thereon, and a flat spring fastened to said guide member and normally lying in position to engage said shoulder for resisting longitudinal movement of the tube but readily movable to release said tube.

CHARLES G. NEWTON.
